WINDOW CONSTRUCTION

John Russell Montgomery, Youngstown, Ohio,
assignor to Truscon Steel Company, Youngs-
town, Ohio, a corporation of Michigan

Application June 14, 1939, Serial No. 279,207

3 Claims. (Cl. 189—67)

This invention relates to metal windows, and more particularly to a novel mounting for casements or ventilator sections.

A primary object of the invention is to provide a novel mounting for swinging casement or ventilator sections which permits the metallic parts of the said section or sash to be pressed against the frame to form a weather tight joint. Ventilators or casements of the type under consideration are usually made of metal angles or channels, which, although normally straight and true, often become slightly warped either in installation or during use, when this occurs it is impossible to make a weather tight joint between the sash and the frame when the sash is closed. Of course weather stripping has been resorted to in many cases to avoid this difficulty. However, this expedient not only involves added expense, but in some cases is undesirable or impractical. Therefore, it becomes important to so mount the sash relative to its frame and when the sash is closed the metallic parts can be more or less compressed or wedged together in tightly fitting relation thereby to fully and evenly contact throughout to provide a weather-proof joint between the sash and frame.

According to the present invention it is proposed to accomplish this result by providing a novel form of pivotal mounting for the hinged edge of the sash which will permit the sash not only to slide but also to shift in opening and closing. On one hand, when the sash is opened this movement permits the bottom edge of the sash to clear the bottom rail or bar of the frame without binding, and, on the other hand, when the sash is closed the parts thereof will be fulcrumed or forced against the parts of the frame so that in event any warping exists it will disappear due to deformation incident to closing pressure. It is, of course, understood that the bars or rails of both the metal sash and frame have a certain amount of resiliency which permits this action to take place. Thus, by providing the present novel mounting for the swinging section it is possible to force all the parts to a weather-tight closure.

More specifically, the invention contemplates a slidable shoe or shoes each having an elongated hole, whose long axis is at right angles to the direction of sliding movement of the shoe, said hole receiving the pivot pin of the sash to afford sufficient clearance between the bottom edge of the sash and the related part of the window frame in opening, and also serving as a limiting stop or abutment which enables the

frame parts of the sash and casement to be yieldably fulcrumed or forced into sealing engagement.

With the above and other objects in view, which will more readily appear as the nature of the invention is better understood, the same consists in the novel construction, combination and arrangements of parts hereinafter more fully described, illustrated and claimed.

A preferred and practical embodiment of the invention is shown in the accompanying drawings, in which:

Figure 1 is an elevation of a metal window having a ventilator or casement section.

Figure 2 is a vertical sectional view taken on the line 2—2 of Figure 1.

Figure 3 is a detail vertical sectional view similar to the lower part of Figure 2 showing the ventilator section during the initial stages of its opening movement, and illustrating how the bottom frame bar thereof clears the lower bar of the frame.

Figure 4 is a view similar to Figure 3 illustrating, in full and dotted lines, additional positions of the ventilator sash in moving to open position.

Figure 5 is a detail elevation, partly in section, of one corner of the ventilating sash and its related frame parts.

Figure 6 is a detail cross-section taken on the line 6—6 of Figure 1.

Similar reference characters designate corresponding parts throughout the several figures of the drawings.

Referring to Figure 1, it will be observed that a metal window construction designated generally as A, is shown. This construction is purely typical and is merely intended to show the environment and adaptation of features intended to be covered by the present invention.

The ventilator section is designated generally as B and is mounted to open and close relative to the window frame designated generally as C.

The frame C consists of a plurality of channel bars, namely, the bottom bar 1 (Figs. 1 and 2) having its outer flange 2 of less depth than its inner flange 3; the side bars 4 and 5, and the top bar 6. The bars 4, 5 and 6 respectively have their inner flanges of less depth than their outer flanges. For example, as shown in Figure 6, the window frame bar 5 has its short flange 5a located at the inner side of the window and its long flange 5b located at the outer side. Likewise, by reference to Figure 2, it will be observed that the short flange 6a of the top bar is located

at the inside while the long flange 6b is located at the outside.

The ventilator or casement section B is also made of channel bars, and the lower bar 7 has its short flange 7a located at the inner side while its long flange 7b is located at the outside and adapted to overlap with the short flange 2 of the bottom bar 1 of the sash. As will also be observed from Figure 2, the short flange 7a of the bottom bar of the sash cooperates with the long flange 3 of the frame bar 1. The side bars 8 and 9 of the sash have their short flanges engaging the inside faces of the long flanges of the side bars 4 and 5 of the window frame. Referring to Figure 6, it will be observed that the side bar 9 of the sash is shown as having its short flange 9a engaging with the inside face of the long flange 5b of the side member 5 of the frame. It will also be observed from this figure that the long flange 9b of the side bar of the sash engages with the short flange 5a of the side bar 5 of the frame. The top bar 10 of the ventilator or casement sash has its short flange 10a engaging with the inside face of the long flange 6b of the top bar 6 of the window frame. The long flange 10b of the top bar 10 of the sash engages with the inner face of the short flange 6a of the top bar of the window frame.

It will, of course, be understood that the ventilator sash B may be provided with a pane of glass or its equivalent.

In each of the side bars 4 and 5 of the window frame, there are mounted suitable sliding shoes 11. These shoes preferably have a frictional fit with the channels of the side bars and may be either of the channel formation shown, or, if desired, may be solid blocks. In either event, the sliding shoes 11 are each provided with an opening 12 in the form of a horizontally elongated hole. These openings are intended to receive the ends of the pivot pins 13 carried by the lower corners of the ventilator or casement section. As will be observed from Figure 5, the pin 13 is slidably mounted in a barrel 14 carried by the bottom frame bar 7 of the ventilator sash C. The pin 13 is preferably provided with a follower spring 15 for urging the pin 13 into engagement with its related opening in the sliding shoes 11. A screw plug 16 may be fitted into the end of the barrel 14 for the purpose of placing the spring 15 under the desired compression.

By means of links 17 pivoted at their upper ends to the frame A and at their lower ends to the sash B, the sash is suspended from the frame A for opening and closing swinging movements.

Due to the suspension of the sash by the links 17 and to the mounting of the pivot pins 13 in horizontally elongated openings in the vertically 60 slideable shoes 11 it will be apparent that when the sash is closed it is bodily movable inwardly and outwardly relative to the frame A so that all of the several bars or rails thereof, which are inherently yieldable, may be pressed tightly 65 against corresponding bars or rails of the frame A, despite any warping of said bars or rails.

When it is desired to open the ventilator section it is merely necessary to exert an inwardly directed force upon the upper part of the same. 70 This results in inward swinging of the lower end portions of the links 17 and in pivoting of the ventilator section about its pivotal connections with the lower end portions of the links 17 and about its pivotal connections with the shoes 11, 75 which shoes slide upwardly as the ventilator

section opens and guide the lower part of the ventilator section upwardly in substantially a straight line.

Figure 3 shows the relative position of parts as the ventilator sections begin to open. As will 5 be observed from this figure, the sliding shoe 11 has moved upwardly from its initial position and the pin 13 has moved to the opposite end of the elongated hole 12 from that shown in Figure 2. It will thus be clear that the short flange 7a of 10 the ventilator or casement section can now clear the long flange 3 of the bottom bar 1 of the window frame. If it is desired to open the ventilator or casement section wider, the continued tilting of the same will move the parts to the 15 position shown in either the full lines or dotted lines in Figure 4. This continued opening movement of the ventilator section will cause the sliding shoe to move further upwardly in the channel of the side bar with the window frame, and, 20 of course, permit all of the window parts to fully clear each other so as not to bind or interfere with the opening movement of the window.

When it is desired to close the ventilator or casement section C it is simply necessary to reverse the operations shown in Figures 4 and 3 so that said section ultimately resumes its closed position as shown in Figure 2. When the section A reaches this position, all of the parts may 30 be sealed in weather-tight relation as previously explained.

From the foregoing, it will be apparent that a distinctive feature of the invention resides in the provision of the horizontal elongated opening or hole in the sliding shoes which permit 35 the pivot pins 13 to shift for the two-fold purpose of enabling the bottom bar of the ventilator section to clear the bottom bar of the window frame in opening and on the other hand to enable 40 all of the parts to be forcibly engaged when the ventilator section is closed.

I claim:

1. In a window, a frame, a sash, and means mounting the sash in the frame for swinging movements between open and closed positions and 45 for bodily movement inwardly and outwardly relative to the frame when the sash is closed, to permit all rails of the sash to be pressed tightly against related rails of the frame, said means including inherently rigid shoes engaged with opposite rails of the frame for sliding movements longitudinally relative thereto and held by said frame rails against movements transversely thereof, said shoes each having an opening elongated transversely relative to the frame, and pivot 50 pins carried by opposite rails of the sash and engaged in the openings of said shoes, respectively.

2. In a window, a frame, a sash, and means mounting the sash in the frame for swinging 60 movements between open and closed positions and for bodily movement inwardly and outwardly relative to the frame when the sash is closed, to permit all rails of the sash to be pressed tightly against related rails of the frame, said means including inherently rigid members engaged with opposite rails of the frame for sliding movements longitudinally relative thereto and held by said frame rails against movements transversely thereof, other members on the sash, certain of 65 said members having openings elongated transversely relative to the window, and pivot pins on the other members engaged in said openings.

3. In a window, a frame comprising top, bottom and side frame members at least the bottom 75

member of which includes an upwardly extending inner flange, a sash comprising top, bottom and side rails at least the bottom rail of which includes a downwardly extending inner flange to abut the outer face of the said flange of the bottom frame member when the sash is closed, links pivoted at their upper ends to the side members of the frame and at their lower ends to the side rails of the sash and suspending the sash for downward and inward swinging movement

from closed to open position, inherently rigid shoes engaged with opposite side members of the frame for vertical sliding movements relative thereto and held by said frame side members against movement transversely with respect thereto, and pin and slot pivotal connections between lower side portions of the sash and said shoes, respectively.

JOHN RUSSELL MONTGOMERY. 10
